UNITED STATES PATENT OFFICE.

WINFIELD S. GROVE, OF MANILA, PHILIPPINE ISLANDS, ASSIGNOR TO FIBRE MACHINERY COMPANY, INC., OF NEW YORK, N. Y., A CORPORATION OF NEW YORK.

METHOD AND APPARATUS FOR DECORTICATING FIBROUS PLANTS.

1,276,348.

Specification of Letters Patent. Patented Aug. 20, 1918.

Application filed July 27, 1916. Serial No. 111,555.

To all whom it may concern:

Be it known that I, WINFIELD S. GROVE, a citizen of the United States, and a resident of the city of Manila, Philippine Islands, have invented certain new and useful Improvements in Methods and Apparatus for Decorticating Fibrous Plants, of which the following is a specification.

The object of the invention is to provide a machine for removing the pulp and waste from fibrous vegetable plants and for extracting cleaned fibers from said plants free from pulp and other waste materials, and the invention also relates to a method which 15 the machine is particularly adapted to perform.

The machine which is the subject of the present invention is particularly adapted for obtaining fiber from the sheaths or strips 20 of the trunk or stalk of the fibrous plant known as abaca and commonly called Manila hemp. The machine, however, can be readily adapted for the treating of sisal, maguey, pineapple or the like.

As a result of my study and work entailed in the extracting of abaca fiber by machinery I have found it desirable (a) to produce a comparatively light and readily portable power-driven fiber-extracting machine carrying its own motive power. This is rendered necessary because of the relatively low yield of fiber from the stalks, the average yield of clean fiber from the abaca plants being under two per cent. (2%) of fiber in weight, 30 as compared with the total weight of the stalk. (b) To design a machine the cleaning or decorticating members of which are constructed so as to extract clean fiber from the stalk with a minimum strain and without bruising, cutting or destroying the cellular construction of the fiber. (c) To design a machine which is automatic, which requires but minimum attendance and which extracts the fiber from the entire length of the sheath, 40 strip or stock and automatically delivers the fiber from the machine free from pulp or waste and comparatively free from water and acids which may have formed part of the substance of the sheath, strip or stock 45 at the commencement of the operation; and (d) to design a machine which will hold the sheath, strip or stock during the operation of cleaning without bruising the fiber, and to reduce to a minimum the strain of the

fiber caused by the pull of the cleaning or 55 decorticating members. The present invention which is the basis of this application embodies all of the above requirements, as will be manifest from what follows.

As showing certain specific embodiments of 60 the invention reference is made to the drawings forming a part of this specification and in which drawings,

Figure 1 is a plan view of a pulp and waste removing or fiber extracting machine. 65

Fig. 2 is an elevation, partially broken away, of the gear or driving side of the machine and is a view looking in the direction of arrow A in Fig. 1.

Fig. 3 is an elevation of the working side 70 or feeding-in side of the machine and is a view looking in the direction of arrow B in Fig. 1.

Fig. 4 is an end elevation of the machine and is a view looking in the direction of the 75 arrow C in Fig. 1. This view may be arbitrarily referred to as a view of the forward or gripping end of the machine.

Fig. 5 is an elevation, partially broken away, showing several sets of decorticating 80 members mounted upon an arm and a part of a mechanism for moving said arm.

Fig. 6 is a transverse sectional view and is a view taken as on the plane indicated by the line 6-6 Fig. 5 looking in the direction 85 of the arrows.

Fig. 7 is a plan view looking downwardly upon the upper end of the swinging arm shown in Figs. 5 and 6. In Fig. 7 two knives or decorticating members of the sets 90 of decorticating members and the holders or carrying members for said knives have been removed, and two knives and their holders have been left in place. Figs. 5, 6 and 7 are views on a somewhat larger scale than shown 95 in Figs. 1 to 4 inclusive.

Fig. 8 is a sectional view of a single set of decorticating members taken as on the plane indicated by the line 8-8 in Figs. 6 and 7 looking in the direction of the arrows. 100 The parts are shown in Fig. 8 on a somewhat larger scale than in Figs. 5, 6 and 7.

Fig. 9 is a side elevation showing a form of mechanism which can be employed for moving the arms carrying the decorticating 105 members.

Fig. 10 is an elevation of the mechanism shown in Fig. 9. In Fig. 10 some of the

parts have been removed so as to show other parts more clearly than they are shown in Fig. 9. Fig. 10 is a view taken as on the plane indicated by the broken line D—D in Fig. 11.

Fig. 11 is a plan view of the gearing shown in Figs. 9 and 10.

Fig. 12 is an end elevation and is a view looking in the direction of the arrow 12 in Fig. 9 or Fig. 11.

Fig. 13 is a sectional view taken as on the plane indicated by the line 13—13 of Fig. 9 looking in the direction of the arrows.

Fig. 14 is a view taken as on the plane indicated by the line 14—14 looking in the direction of the arrows (see Fig. 9).

Fig. 15 is a view taken as on the plane indicated by the line 15—15 looking in the direction of the arrows (see Fig. 9).

20 In the form of machine shown in Figs. 1 to 4 there is a main or supporting frame 1. This main frame is preferably made of commercial rolled shapes, suitably tied together in order to provide a simple, light and rigid construction. As, however, the manner of constructing such a frame will be manifest to persons skilled in the art a detailed description thereof is deemed unnecessary. Moreover the construction of such 25 a frame is clearly indicated on the drawings.

This frame is mounted on rollers or wheels 2 whereby the frame and all the parts carried thereby can be readily transported from one place to another as desired. The machine is provided with a drum or fiber resisting member 3. In the construction shown this fiber resisting member is circular in form, thus providing a curved periphery. The drum, as constructed, comprises a strip of sheet metal 4 that is bent around and secured to the two angle irons 5 and 5'. Radial braces 6 are connected to these angle irons 5 and 5' and are also secured to bearings 7 that float upon a main 30 shaft 8. The lower portion of the angle iron 5' is directly connected or anchored to the main frame 1, as through the medium of the anchor or brace 9 shown in Fig. 4 and anchors or braces 9', 9'' shown in Fig. 3.

35 Brace 9 serves to secure the lower portion of the drum fixedly relative to the main frame, and braces 9' and 9'' coöperate with the lower brace and thus serve to secure the drum as a whole in a proper position relative to the main frame. Bracing members 10 and 11 strengthen the frame against vertical sidewise distortion. The radial braces 6 being secured to the floating bearings 7 serve to maintain the fiber resisting member or drum 3 in place relative to the main 40 shaft 8. The main shaft 8 is mounted in main bearings or pillow blocks 12 which are secured to the upper longitudinal members 13 of the main frame 1. The main bearings, 45 main shaft, floating bearings 7 and diagonal

braces 6 coöperate with the anchors or braces 9, 9' and 9'' to position and hold the fiber resisting member or drum 3 in place.

A main gear 14 is carried by the shaft 8 but can revolve relative to the shaft. A 70 pair of arms, one designated as 15 and the other as 16, is secured to this main gear, thus providing a construction in which the pair of arms swing about a fixed axis, to wit, about the axis of the main shaft 8. 75 The arm 15 carries a number of sets or pairs of opposing decorticating members designated as 15^a, 15^b, 15^c and 15^d. Each set or pair of these decorticating members comprises a decorticating tool or knife X and 80 an inner decorticating or resisting member Y, as clearly shown in Fig. 8. The knives X are mounted so that they can move toward and from the resisting members Y as will hereinafter appear.

85 The arm 16 carries several pairs of sets of decorticating members which are similar in their general construction to those carried by the arm 15, but an inspection of the drawings, and particularly Fig. 3 thereof, 90 will make it clear that the knives on the arm 15 are arranged to strip the fiber when the arm 15 is being swung about its axis, as in a counter-clockwise direction, whereas the decorticating members carried by the arm 16 95 are arranged to clean the fiber when the arm 16 is moving, as in a clockwise direction, about the same axis which coincides with the arms of the main shaft 8. The sets of decorticating members on arm 16 will herein- 100 after be referred to as subsequent decorticating members.

The main gear 14 to which the arms 15 and 16 are secured is driven from the continuously rotating driving shaft 115 of a 105 motor, as M, through a train of gearing comprising intermittently operated gears which are constructed and arranged so that with a motor operating continuously there can be imparted to the gear 14 and consequently to the swinging arms 15 and 16 secured thereto swinging movements in opposite directions. In other words, the gear 14 can be driven in a direction to move the arm 15 in the direction of the arrow marked 110 A A, whereby the initial decorticating members on the swinging arm 15 can be performing their function of stripping the fiber in an end portion of the strip or stock to be cleaned and removing the pulp and 115 waste. This is the first cleaning operation to take place. It is manifest that the strip of stock being operated on is detached from the plant or mother stock and during this cleaning operation the butt end H of the 120 strip or stock S is the part which is preferably treated.

125 Just prior to this and while the cleaning of the butt end of the strip is being performed the strip or stock is seized by the 130

gripping mechanism at 17, hereinafter referred to as initial gripping mechanism. This mechanism comprises a movable jaw 18 and an opposing member or fixed jaw 19 which fixed jaw may be considered as a part of the main body of the resisting member. The mechanism for moving this jaw 18 will subsequently be described.

After the butt end of the stock has been cleaned a pusher or whip P is brought into operation and forces the cleaned fiber of the butt end into a second gripping mechanism 20, which second gripping mechanism is hereinafter referred to as subsequent gripping mechanism. Before the cleaned fibers are gripped by 20 the arms 15 and 16 have been moved in the direction of the arrow marked A A (viz. in the counter-clockwise direction see Fig. 3) to the dotted position indicated in Fig. 2. The dotted position shows that the initial decorticating members have moved past the butt end H of the stock and that the opposing members of the subsequent decorticating members on the arm 16 remain on opposite sides of the fiber which has already been cleaned. The decorticating members on the arm 16 are then brought into operative relation and the gear 14 carrying the arms 15 and 16 is caused to move in the direction indicated by the arrow B B, to wit, in a clockwise direction, (see Fig. 3) until the decorticating members of the arm 16 have completed the cleaning of the strip or stock in the machine. In other words, the gear 14 and the arms thereupon make a complete revolution, plus a sufficient movement to bring the members back to their initial position shown in full lines in Fig. 3.

In the machine as designed the gear 14 moves one-sixth of a revolution in a counter-clockwise direction (see Fig. 3), whereby the set of initial decorticating members or tools on arm 15 will be moved from their initial position to a position where they will completely clean the butt end of the strip or stock being treated and thereafter the gear 14 will be moved a revolution and a sixth of a revolution, in a clockwise direction, so that said subsequent decorticating members or tools on the arm 16 can be employed to clean the rest of the strip or stock and will also be brought to the initial full line position shown in Fig. 3. It will here be noted that during the time said subsequent decorticating members are being moved in the counter-clockwise direction, as indicated by the arrow A A, they are functionally inoperative. After the decorticating members reach the dotted position shown in Fig. 2 the subsequent gripping mechanism is closed and the initial gripping mechanism is opened. During the movement in the clockwise direction the initial decorticating members on arm

15 are functionally inoperative. In Fig. 3 and in the full line position of Fig. 2, the parts are shown in the position which they occupy after a strip or stock has been inserted in the machine and prior to any other parts of the machine being moved for the purpose of gripping or cleaning the strip or stock.

As previously indicated the construction of the swinging arm 15 and the manner of mounting the decorticating members thereupon are substantially the same as the construction of the swinging arm 16 and the manner of mounting the decorticating members thereupon; therefore a description of only one of these arms will be given.

In Fig. 5 there is illustrated a part of the main gear 14 to which the arm 15 is secured through the medium of straps or spacing members 21 that are directly secured to the gear 14 by bolts or screws 22. The free end of the arm 15 has a block 23 that extends laterally over the fiber resisting member or drum 3. This block carries the resisting members Y which are held in place, as by means of bolts 24. The resisting members Y may be referred to as inner decorticating members because they are nearest to the drum and are operatively located between the inner side of the stock 90 being cleaned and the drum. The knives or decorticating members 15^a, 15^b, 15^c and 15^d are secured, respectively, to the outer end 25 of a holding member 26. Each knife may be referred to as an outer tool or outer decorticating member because it is operatively located farthest from the drum and on the outer side of the stock on the drum. To each knife holding member there is attached one end of a tensioning spring 27, 100 the other end of which spring is adjustably secured as by a nut and screw connection 28 to a part of the swinging arm 15. Due to the connection just referred to the desired tension can be imparted to the springs and in this way the pressure of any individual knife or decorticating member against the stock being cleaned can be regulated. Each of these knife holding members is located in a guideway 29 and is held in place in 110 said guideway as by means of overlapping plates 30 and 31. Each of the knife holders is provided with a projection 32 carrying an anti-friction roller 33. The knife member or outer decorticating tool, which is the 115 movable or yielding decorticating member of each set, is always maintained in operative position in respect to its companion resisting member by means of the tension of the springs 27, except at such times as it is 120 caused to be held in an inoperative position due to the roller 33 engaging a member or members arranged to cause the tools to be held in said inoperative position. The 125 members which cause the tools to be held in 130

- inoperative position are cams or tracks which will be subsequently described more in detail. The cams or tracks which control the movable decorticating tools or 5 knives on arm 15 are designated by G and the set of cams or tracks which controls the movable decorticating tools or knives on arm 16 are designated by J (see Fig. 2). The movable or yielding decorticating member, to wit the knife X, is in effect pivotally mounted at 34 upon the knife holding member 26 and when properly adjusted relative to its unyielding resisting member Y is secured in place by the screw 35 which 10 passes through a slotted portion 36. This slotted portion can be in either the knife or the knife holder. The knife is therefore finally fixedly but adjustably secured in place in its holder which can yield.
- 15 The block 23 has control stops or plugs 37 which are seated in sockets 38 in the block. These stops or plugs are held in place through the medium of a small pin 39 which is normally pressed inwardly by the spring 20 40. The contact stops can be relied upon to positively limit the movement of each knife toward its companion resisting member whereby the opposing decorticating members will always be maintained at least 25 a predetermined distance apart. The yielding holder is located at only one end of the knife, that is at the end of the knife which is nearest to the gear or driving side of the machine, or in other words away from 30 the feeding-in side of the machine. There is no direct support for the end of the knife at the working side or feeding-in side of the machine, except that afforded by a projection 41 (see Fig. 8), because it is desirable 35 to pass the stock sidewise into the space between the knives and their companion resisting members. In order, however, to provide an additional support for the end of the knife at the working side of the machine 40 45 a projection or supporting member 41 is provided for each knife. This projection is shown in Fig. 8 and also in Fig. 7. Each knife can be readily changed by removing its screw 35 and by sliding the knife along the pin at 34 which provides pivotal connection until the enlarged portion of the slot 42 can pass over the head of the pin at 34.
- 50 One side of the machine has heretofore 55 been referred to as the working side or feeding-in side of the machine. The side thus referred to is the side which is shown at the left hand of Fig. 1. This particular side has been referred to as the working side of the machine because the operator or feeder of the machine will stand on this side. On this side there is a table for supporting the work pieces or strips of stock prior to their introduction into the machine and the strips 60 65 are pushed from the table to the left over

the fiber resisting member or drum 3. When the strips are moved from the table over the resisting member 3 they first occupy the position shown in Fig. 3; that is, they enter the space between the inner and outer 70 members of each set of decorticating members on the swinging arm 15 and swinging arm 16. It will be observed that the resisting or inner members of each of these sets of decorticating tools are at this time located 75 between the fiber to be cleaned and the fiber resisting member or drum 3. In other words, the inner resisting members always travel, during the time when they are operating to assist in the cleaning of a strip, between the strip or fiber being treated and the fiber resisting members. 80

The feeding table is designated by T and it comprises fixed supports FS and movable supports MS. These supports are substantially in alignment and in effect form the upper portion of a table. Each of the movable supports MS has an upwardly extending horn or projection and is actuated at a certain timed relation with respect to the 90 movement of the swinging arms through the medium of the mechanism O that is actuated from a cam on the main shaft 8 (see Fig. 4). The movable supports MS can move from the position shown in Fig. 1 to the left 95 or over the fiber resisting member or drum 3, thus moving the fiber or stalk to be treated into the position indicated by the broken line in Fig. 3. After the decorticating tools have completely cleaned the strip and have 100 left the last end of the strip they continue their movement in the same direction and both the knives and the resisting members finally pass over the cleaned butt end of the strip, which is then supported on the resisting member or drum 3, to their initial position. Thereafter, the subsequent gripping mechanism 20 is released and an ejecting mechanism K is brought into operation to remove the cleaned fiber from the fiber 110 resisting member or drum 3 and convey the cleaned fiber to a receiving rack or arms 106. 105

The member 3 has heretofore been referred to as the fiber resisting member. An inspection of Fig. 3 will make it clear that 115 while the initial decorticating members on the arm 15 are being moved in the direction of the arrows A A to clean the butt end of the strip, stock is not only gripped by the initial gripping mechanism at 17 but due 120 to the general curvature of the resisting member 3 some of the strain is directly absorbed by the resisting member 3. Likewise when said subsequent decorticating tools on the arm 16 are being moved in the direction 125 of the arrow B B said initial gripping member at 17 is open and the fibers are gripped by said subsequent gripping mechanism at 20. The strain imparted to the fiber during the cleaning operation is not all transmitted 130

to the place where they are gripped by the grippers 20 but some of it is absorbed by the fiber pressing against the resisting member 3, the action being similar to that of the 5 belt on the periphery or face of a pulley which it is engaging.

Reference has heretofore been made to the initial gripping mechanism at 17. The movable jaw member 18 of this mechanism has a 10 shank 44 which is slideable in a guideway 45 that is secured to the main frame 1 by braces 46. The lower end of this shank 44 has a member 47 that is engaged by a controlling cam 48 on the main shaft 8. This shaft 8 is 15 driven so that it makes one complete revolution for each cycle of the cleaning operation and the cam is constructed so that it brings the movable jaw 18 into gripping position prior to the time that the decorticating 20 members on arm 15 are operating to clean the butt end of the strip and holds said jaw in said position during said time. The closing of the jaw at 17 takes place immediately after the strips have been inserted, 25 as heretofore described, in the position shown in Fig. 3. A spring 49 is relied upon to open or lift the jaw 18 when permitted to do so by the controlling cam, this opening taking place after the decorticating 30 members have cleaned the butt ends of the strips and also after the pusher P has moved the ends of the cleaned portions of the strips into the space between the jaws of said subsequent gripping mechanism 20; and 35 also after the gripping mechanism 20 has actually gripped the ends thus positioned therein. The gripping mechanism 20 is closed through the medium of the lever 50 which is pivotally mounted upon a fulcrum 40 51 carried by the main frame 1 and which lever is actuated by means of a controlling cam 52 that is on the main shaft 8. The lever 50 has an anti-friction roller 53, which is the member that directly engages this 45 cam. A spring 54 engages said lever 50 and operates to open the gripping mechanism 20 when the cam 52 permits the gripping mechanism to be opened. The pusher P heretofore mentioned may sometimes be referred 50 to as a whip because it moves quickly and whips the cleaned ends of the fiber into the space between the jaws of the gripping mechanism 20. The outer end of the lever 50 is in the form of a corrugated jaw, though 55 a plain jaw may be employed, and this provides the movable jaw 56 which cooperates with a relatively fixed jaw or member 55. The pusher P is in a retracted position, that is away from the gripping jaws from the 60 time prior to the introducing of a strip to be treated into the machine until after the butt end of the strip has been cleaned by the initial decorticating members on arm 15. Upon the completion of the cleaning of the 65 butt end of the strip by the decorticating

members on arm 15 the pusher or whip P is caused to move quickly inwardly by the spring 57 which is allowed to act due to the controlling cam 58 releasing the roller 59 that is on the end of the slidably mounted 70 rod 60, the latter of which is connected at 61 to the lever 62 of the pusher P. This lever 62 is fulcrumed on the frame at 63. The pusher together with the ends which it conveys into the jaws is gripped between 75 the jaws and is held in gripped position during the time that said subsequent decorticating members on arm 16 are serving to clean the rest of the strip.

In the form of apparatus shown in Figs. 1 to 4 the power for operating the machine is derived from the motor M having a continuously rotating shaft 115 which provides a driving shaft. This motor drives a bevel gear 64 by means of the pinion and chain 85 gearing which comprises the sprocket 65, chain 66, sprocket 67, shaft 68, sprocket 69, chain 70 and sprocket 71, the latter of which is secured to the bevel gear 64. The bevel gear 64 meshes with a bevel gear 72 that in 90 turn meshes with another bevel gear 73. A shaft 74 passes through the bevel gears 64 and 73 and this shaft can be driven by means of either one of these gears when a movable clutch 75 is positioned so as to engage a corresponding clutch portion of either the gear 64 or gear 73. The shaft 74 has connected to it a spur-gear 76 (see Figs. 2 and 4) that meshes with and drives the main gear 14. 95 The clutch member 75 is positioned in operative engagement with either the clutch part of gear 64 or the clutch part of gear 73 by means of a cam 77 which moves the yoke 78. This cam 77 is continuously rotated through 100 the train of gearing which comprises the shaft 68 to which the gears 67 and 69 are connected, a gear 79 that is carried on the shaft 68, a gear 80, shaft 81, gear 82, gear 83 and shaft 84, the latter of which carries the cam 77. To this shaft 84 there is also secured a sprocket 85 which in turn drives, by means of a chain 86, and sprocket 87, the main shaft 8. The main shaft 8 and the cam controlling member 77 actuated thereby both continuously rotate. In other words, 105 cam 77 and shaft 8 do not reverse their movement at any time during the operation of the machine. It has heretofore been made clear that the main shaft 8 carries the cams which control the opening and closing 110 of the initial gripping mechanism, the closing and opening of the subsequent gripping mechanism, the operation of the pusher or whip P, the operation of the ejecting mechanism K and of the feeding-in mechanism 115 whereby a new series of operations can be instituted. The gearing and cams are constructed and timed so that the movement of the different parts will take place in the manner described. The cam 77 is con- 120 125 130

6
structed and geared so that it will operate to cause an engagement of the clutch member 75 with bevel gear 73 whereby said bevel gear, through the medium of the clutch 75, 5 shaft 74 and gear 76, will turn the gear 14 in the counter-clockwise direction, indicated by the arrow A A in Fig. 3, to first clean the butt end of the strip which is in position to be cleaned. When the pusher P has placed 10 the cleaned end in the gripping mechanism 20 and when said subsequent gripping mechanism 20 has gripped the cleaned fiber thus positioned, then the clutch member 75 is moved into engagement with the clutch portion 15 of the other bevel gear, to wit, gear 64, whereby a reverse movement will be imparted to the shaft 74, the gear 76 and the main gear 14 so that said main gear and said subsequent decorticating members will be 20 caused to move in a clockwise direction indicated by the arrow B B in Fig. 3. The movement in this direction will be more than a complete revolution. In other words, it will be sufficient to carry the decorticating 25 members to their initial position, to wit, the position where the stock was first fed into the machine for the purpose of being cleaned. The cam 77 is constructed so that when the members reach this position the clutch 75 is 30 automatically disengaged whereby a new sequence of operation can be adequately performed.

It has heretofore been made clear that the initial set of decorticating members on the 35 arm 15 operate only when moving in the direction indicated by arrows A A and that the subsequent decorticating members on the arm 16 operate only when traveling in the direction indicated by arrow B B. The decorticating members on arm 15 are under the 40 control of a track construction G while the decorticating members on arm 16 are under the control of the track construction J. When the arm 15 is in the initial position, to 45 wit, the full line position shown in Fig. 3, the several rollers 33 are pressed against a stationary portion 88 of the track G, due to the force of the springs 27. As the arm 15 starts to move in the direction of the arrow 50 A A each of the rollers 33 successively moves from the stationary portion 88 upon a switch 89. As these rollers successively pass upon the switch 89 they pass under the free end of another switch member 90. The switch 55 member 89 yields under the pressure of the rollers traveling along the same and allows all of the rollers to move to a position where they can pass under the fixed portion 91 of the track G. With the movement of each 60 of the decorticating members in the manner just described each set of initial decorticating members is successively brought into operative engagement with the butt ends of the strip or strips of stock to be cleaned and said 65 initial decorticating members remain in en-

gagement with said strip or strips of stock until passing beyond the extreme butt end or ends which have been fed to register into the machine. After the initial decorticating tools or members on arm 15 have passed 70 from the butt end of the strip the portion which has been treated drops upon the resisting member or drum 3 and is gripped by the grippers at 20 having been pushed into position to be gripped by the pusher P. 75

The opposing members of the sets of initial decorticating members on arm 15, and this includes not only the knives but the resistance blocks, pass over or outside of the fiber which is on the resisting member or 80 drum 3, but not in engagement with said fiber, while said initial decorticating members are being moved in the direction of the arrow B B. It will presently be explained how said subsequent decorticating members 85 on arm 16 are brought into operation as said arm moves in the direction of the arrow B B. As the main gear starts to travel in the direction of the arrow B B the rollers 33 on arm 15 are under the fixed portion of the 90 track 91 and they pass from under this fixed portion 91 under the movable member or switch 89 which is normally held in the position shown in Fig. 2 by means of a spring 89', to and under or behind the fixed 95 member 88 upon which the rollers rested when in their initial position. The yieldable or movable members of each set of subsequent decorticating members on arm 16 are held in inoperative position during the 100 movement of the arm in the direction of the arrow A A by means of rollers 33 resting on the stationary member 92 of track J. Before the arm 16 reaches the end of its travel in the direction of the arrow A A each of 105 the yieldable decorticating members that are held in an inoperative position by said fixed portion 92 of the track passes from said fixed portion over a movable member or switch 93 to an abutment 94 or fixed portion 110 of the track. This abutment 94 is at such a position that it will hold the yielding or movable knives of the decorticating members only a short distance away from the fiber which has just been cleaned by the initial 115 sets of decorticating members. The switch 93 is normally held in the position shown in Fig. 2 by a spring 93'. This spring yields under the pressure of the rollers 33 when traveling from the member 92 to 94, but is 120 strong enough to hold the switch in the position shown in Fig. 2 when the latter is not pressed by the rollers. The rollers 33 of the subsequent decorticating members successively pass from the abutment or fixed portion 125 94, when the arm 16 is moved in the direction of the arrow B B.

There is now nothing to prevent the decorticating members on arm 16 from operatively engaging the work-pieces or strips of 130

stock which are located between the sets of subsequent decorticating members or tools on arm 16 and therefore the decorticating members or tools on said arm 16 can perform their function as they are being moved in the direction of the arrow B B to their initial position. During the last portion of the movement in the direction of the arrow B B the rollers 33 on the movable tools carried by arm 15 and also the rollers 33 on the movable decorticating tools on arm 16 engage certain switches and pass upon certain portions of the tracks G and J whereby the movable or yieldable decorticating tools or knives are forced outwardly to their initial inoperative position. As the tools on arm 15 are passing through the latter part of their movement in the direction of the arrow B B the rollers 33 successively engage a member or switch 97. This member 97 has been made yielding so that the free end thereof can be forced outwardly by the rollers 33 on arm 15 engaging the same, if said arm should over travel in the direction 25 of the arrow A A, as due to a breakage, but otherwise this member 97 may be considered as a relatively stationary switch that serves to successively force outwardly the decorticating knives or yieldable decorticating members, as the rollers 33 travel along said switch 97 while said arm 15 is being swung toward its initial position in the latter part 30 of its movement in the direction of arrow B B. From the switch member 97 the rollers 33 pass upon the relatively stationary member 91, finally over another switch 90 to the initial position on stationary member 88. The switch 90 is normally spring-pressed outwardly to the position shown in 35 Fig. 2 and the free end thereof extends to the relatively stationary track member 88 whereby as the rollers 33 are passing over the switch 90 they force the latter downward so that there is a comparatively smooth 40 travel from the track 91 over the switch 90 to the track member 88. As to the tools on arm 16, the movement to initial position is accomplished by the rollers 33 successively engaging a member 95. This member 95 has 45 been made yieldable merely to permit the rollers to pass thereunder and lift the same in case a break should occur whereby the arm 16 would be moved in the direction of the arrow A A more than it should. In the 50 normal performing of its function, however, this member 95 operates as a relatively stationary member and the lower end thereof is positioned so that it is in the path of the rollers 33 as they move in the direction of 55 the arrow B B. In the further movement in the direction of the arrow B B the rollers 33 on arm 16 pass over a member 96 the free end of which can yield until it presses upon the fixed member 92 whereby the rollers 33 60 can pass directly from the member 96 to the member 92. In passing from the member 96 to member 92 it will be observed that the rollers do not engage the switch 93 heretofore referred to and at the termination of the movement in the direction of the arrow B B the track construction J just described will cause the movable decorticating tools to assume the initial position shown in Fig. 2. As the tools on arm 16 are moved in the direction of the arrow B B so the tools 75 on arm 15 will also move in the direction of the arrow B B. The tools on arm 16 and the tools on arm 15 each have the same angular movement not only in the direction of the arrow A A but also in the direction of B B. 80 When the decorticating members on both the arms 15 and 16 finally reach their initial position as shown in Fig. 2 they are no longer in engagement with the work-piece or stock which has thus been treated by 85 them. In other words, the piece of stock which has been treated is now resting upon the resisting member or drum 3 and the sets of decorticating members or tools on each of the arms are outside of the cleaned 90 fiber which is resting in the space Z upon the resisting member or drum 3, (see Fig. 6). 95 The ejecting mechanism or kick-off is now brought into operation before any feeding-in takes place and this kick-off comprises a series of radiating arms 99 which are pivotally mounted upon fixed fulcrum points 100. The outer ends 101 of each of these arms normally occupy the position shown in Fig. 1; that is just inside or behind the sheet metal or the periphery of the resisting member or drum 3. The inner ends 102 of each of these arms are operated as by means of a sleeve 103 which is in turn actuated by the controlling cam 104 that is carried by the 100 shaft 8. This cam is shaped so as to effect a quick movement of the sleeve 103 in the proper direction to move the ends 101 of the arms so as to force said outer ends of the arms toward the feeding-in side of the machine; in other words, this causes the outer ends of the arms to project through the slots 105 in the resisting member or drum 3 and to move along said slotted portion until the resisting member is free of all fiber which 105 has been cleaned. The fiber thus conveyed or ejected drops from the resisting member or drum upon a receiving rack or fixed arms 106 from which the cleaned fiber can be taken at the convenience of the operator. The 110 outer ends 101 of the ejecting arms are curved so that the fiber being ejected from the resisting member or drum will not be lifted from the receiving drum and so that the arms can slide upwardly along the fiber as the arms in turn are causing the fiber to slide laterally over the face of the resisting member or drum 3. The rack members or fixed arms 106 are secured in place by being 115 connected to the angle 5' which constitutes 120 125 130

a part of the frame of the resisting member or drum. The fulerumed point 100 is carried on a member 107 that is secured to this same angle 5'. The receiving racks or arms 106 are shaped so that the cleaned fiber will be automatically conveyed a distance from the drum by its own weight.

As a matter of fact the portion of each arm which ultimately supports the cleaned fiber until the latter is removed from the machine is directly located underneath the feeding table, thus providing a compact construction with the cleaned fiber out of the way of the strips to be cleaned. After the cleaned fiber has been removed from its position on the receiving rack the feeding-in mechanism is brought into operation and another cycle of operations can be performed.

The feeding-in mechanism or table comprises the fixed supports FS heretofore referred to and the movable supports MS having horns or projections 43. The movable supports with the horns thereupon are the members which are moved inwardly to force 25 the strip of stock to position to be operated upon and the movable members MS are actuated by means of the slotted levers 108, levers 109, lever 110 and cam 111, the latter of which is secured to and carried by the shaft 30 8. The movable members MS are normally held in their retracted position shown in Fig. 4 by means of a spring 112 and they are moved so as to feed the stock to the machine by the controlling cam 111. A series 35 of arms 113 provide a magazine for holding a number of work-pieces or strips of stock to be cleaned and from this magazine the required number of strips of stock are placed upon the feeding mechanism or table by the operator of the machine. The feeding-in mechanism performs the function of transferring the strips of stock or work-pieces to be treated from the feed table into the proper space between the opposing members of the 40 decorticating tools or members. The magazine and feed table are supported in place by any suitable framing which comprises for instance the members 114 that are secured to the main frame 1.

50 The main gear designated 14 in the construction shown in Figs. 9 to 15 inclusive corresponds in its function and mode of operation to the gear 14 heretofore described and shown, for instance in Fig. 5. This main gear 14 is driven from a continuously rotating shaft 115 that constitutes a part of a continuously operating member M'. This member M' may be any member which is continuously driven from a suitable source 55 of power, or it may be a continuously operating motor, such as is indicated in the construction shown in Figs. 1 to 4. The shaft 115 has secured thereto a pinion 116 which serves to continuously rotate a gear 117 in one direction and a gear 118 that is

in mesh with said gear 117 in another direction. The gears 117 and 118 are twin gears operating in opposite directions. The gear 117 is mounted upon a shaft 119 and this gear has secured thereto, by means of 70 suitable bolts 120, an intermittent gear 121 and a cam 122. The intermittent gear 121 coöperates with and serves to drive another intermittent gear 123, the latter of which is carried upon and secured to a shaft 124. 75 The last-mentioned shaft has secured thereto a gear 125 and thus the gears 123 and 125 will rotate in unison or together when one of them is driving. The construction of gears 121 and 123 is such that for a portion 80 of a period, when the gear 117 is being rotated, the gear 121 will be imparting a rotary movement to the gear 123 and so that during another period of the rotation of the gear 117 the gear 121 will be holding the 85 gear 123 fixed and in a dwell. It will be observed, however, that the gear 121 always rotates with the gear 117, and the dwell or holding of the gear 123 and the gear which moves in unison with it, to wit, gear 90 125, is accomplished through the medium of the intermittent gear construction provided by the gears 121 and 123. The function of the cam 122 will subsequently be described. The gear 118 has secured to it by means of 95 the bolts 126 one member of a Geneva gear construction, to wit, the driving member 127 and also a cam member 128. The driving member 127 of the Geneva gear construction comprises a lock-plate 127^a (sometimes referred to as a roller-plate) and a driving pin or driving roller 127^b. This member 127 of the Geneva gear construction coöperates with a notched member 129 which constitutes the driven member of the Geneva 100 gear construction. The member 129 has a set of dwells 129^a and a set of notched or roller engaging portions 129^b. The lock-plate portion 127^a engages a dwell portion 105 129^a so as to hold the member 129 in one 110 position during a portion of the time when the gear 118 and the attached driving member 127 of the Geneva gear are being rotated. The gear 118 is mounted upon a shaft 115' which is supported in any suitable bearing on the frame. The driven notched member 129 of the Geneva gear construction is keyed to and mounted upon a shaft 130 upon which a gear 131 is mounted and to which said gear is keyed so that the gear 131 and 120 the driven member 129 of the Geneva gear will move in unison each time the driven member of the Geneva gear is partially rotated. The gear 131 may be considered one gear of a set of twin gears, the other of 125 which is the gear 125 heretofore described. A gear 132 meshes at one time with the gear 131 and at another time with the gear 125. The gear 132 is shown in Figs. 9 and 10 as being in mesh with the gear 131. The gear 130

132 is keyed to a shaft 133 to which a gear 134 is also keyed so that the gears 132 and 134 will move together. The gear 134 is always in mesh with the main gear 14. The 5 gear 132, shaft 133 and gear 134 are carried on a swinging arm or lever 135 that is mounted so that it can swing on the main shaft 8 which is the same as the main shaft 8 heretofore described. The gear 132, shaft 10 133 and gear 134 constitute a floating gear construction which is movable from a position where it can be readily driven by gear 131 to a position where it can be driven by gear 125 and vice versa. The lower end of 15 the lever or arm 135 carries a roller 136. The center of this roller is preferably on the line passing through the centers of the shafts 119 and 118' about which the cams 122 and 128, respectively, rotate. These cams 20 continuously rotate since they are secured to the continuously rotating gears 117 and 118 that move in opposite directions and the radius of the cams is such that one of the cams engages or nearly engages one side of, 25 the roller 136 while the other can engage or nearly engages the other side of the roller. In other words, the sum of the adjacent radii of the cams remains constant so that the space between the cams will remain constant whereby the roller and the free end 30 of the lever will always be under control. The cams are shaped and arranged so that when one of the cams is serving to force the lower end of the lever to the left, for 35 instance, the other cam will have a dwell therein so as to allow the cam to be thus forced. These two cams in effect constitute a single motion cam which can positively throw the lower end of the lever or arm 135 40 to either the right or the left and also hold the lower end of this lever in its adjusted position. When the lower end of the lever 135 is held in its extreme position to the left, as shown in Figs. 9 and 10, the gear 45 132 is in mesh with the gear 131 and rotary motion is imparted to the main gear 14 in the direction of the arrow A A. The movement imparted to the main gear 14 from the continuously rotating main shaft 115 is 50 through the pinion 116, gear 117, gear 118, roller 127^b of the driving member of the Geneva gear construction, driven member 129 of the Geneva gear construction (which is driven by the roller 127^b engaging the 55 notched portion 129^b) the gear 131, gear 132, gear 134 and finally the main gear 14. When the continued movement of the gears 117 and 118 is sufficient for the cams which are secured thereto to move the lower end 60 of the lever or arm 135 to the right, where gear 132 will mesh with gear 125, the main gear 14 will be driven in the direction indicated by the arrow B B from the continuously rotating shaft 115 through the gear 65 which comprises the pinion 116, gear 117,

the set of intermittent gears 121 and 123, the gear 125, gear 132, gear 134 and finally gear 114.

The construction and arrangement of the cams 122 and 128 is such that they may be 70 considered as a single cam mechanism for positively moving the lever 135 to the right or left and for holding it in its adjusted position. The construction of the intermittent gears 121 and 123 and their arrangement 75 relative to the set of cams just referred to are such that the gear 123 and gear 125 are held in a definite locked position by the roller or plate member 121' of the gear 121 engaging the dwell portion 123' of the gear 123 and 80 consequently the gear 132 can be placed in mesh with the gear 125 by the set of cams while the gear 125 is being held stationary. The set of Geneva gears is constructed and 85 mounted relatively to the set of cams so that the gear 131 is held in a stationary or locked position, by the locking plate 127^a of the Geneva gear driving member engaging the dwell 129^a of the Geneva gear driven member, whereby when the Geneva gear 90 driven member and the gear 131 are thus held stationary the gear 132 can be moved from engagement with the gear 131 to and into engagement with the then stationary gear 125. The construction is also such that 95 the gear 132 can be moved at a subsequent period from engagement with the gear 131 to and into engagement with the then stationary gear 125. The construction is also such that the gear 132 can be moved at a 100 subsequent period from engagement with the gear 125 (when held stationary) to and into mesh with the gear 131 (when held stationary) after the gear 125 has rotated the gear 132 the desired number of revolutions. 105

The main shaft 8 in the construction shown in Fig. 9 may be continuously rotated by means of the mechanism comprising the indicated gear 85', the indicated chain 86' and the indicated gear 87'. It will be manifest 110 that if for any reason it is desired to drive the main shaft 8 in an opposite direction, due to the cam construction thereupon, this can be readily accomplished by transferring the gear 85' so that it will be associated and be 115 driven in unison with the gear 117 instead of with the gear 118, as is done in the construction shown in Fig. 9.

The sets of gearing shown in Figs. 1 to 7 inclusive and the set of gearing also just described and shown in Figs. 9 to 15 are constructed, arranged and timed so that the following cycles of operations can take place. For instance, the machine may be considered to be based upon a three second cycle for a 125 complete operation. During the first period, which may be considered a one second period, there is a stop, for the entire period, of all movements of the decorticating members about the resisting member or drum. 130

During this period the subsequent gripping mechanism, at 20, opens, the pusher P is then automatically forced outwardly by its spring and the cleaned fiber from the butt end of 5 the strip or stock, previously cleaned or treated, is released. This is followed by the kick-off mechanism K ejecting said strip or stock and moving the same to a position where it can drop upon the receiving racks 10 or arms 106. As soon as said previously cleaned strip or stock has been ejected, strips or pieces of stock to be cleaned are fed into the machine by the mechanism which comprises the movable supports MS that serve 15 to move the strips or pieces of stock S from the feed tables T to a position over the resisting member or drum 3 and into the spaces between the separated opposed members of the sets of decorticating members or tools 20 which are upon the arms 15 and 16. When in this position the butt end H of the strip or stock drops down and occupies the dotted position shown in the right half of Fig. 2 and the small or tip end of the strip or stock 25 drops down and occupies the dotted position marked S' in said figure. Shortly after the stock has been positioned in the machine the controlling cam 48 engages the projecting member 47 (see Fig. 4) and forces the movable jaw 18 of the initial gripping mechanism downwardly whereby the stock to be treated will be first gripped or seized between the movable member 18 and its opposing jaw 19 and thus be secured to the resisting member 3 and properly positioned relative thereto. As the motor continues to revolve and drive the main gear 14 through the train of gearing heretofore described it will 35 first cause the sets of decorticating members 40 on arms 15 and 16 to travel in the direction indicated by the arrow A A in Fig. 2 or Fig. 3. During the travel in this direction the sets of decorticating members on arm 15 are permitted, due to the track construction G heretofore described, to come 45 into operation and clean the butt end H of the strip. Until nearly the end of the movement in this direction the decorticating members on arm 16 are prevented from pressing 50 between them the stock to be cleaned. Near the end, however, of the movement in the direction of the arrow A A the decorticating members on arm 16, to wit, said subsequent decorticating members, are allowed 55 to approach each other but they are prevented, by means of the small stationary part 94 of the track J, from pressing the strip or stock between them until they have moved a short distance in the reverse direction, to 60 wit, in the direction of arrow B B. The movement in the direction of A A occupies the period of one-fifth of a second and at the end of this movement the initial decorticating members on arm 15 may be considered 65 to be below or beyond the subsequent grip-

ping mechanism 20, whereas said subsequent decorticating members on arm 16 may be considered to be above the gripping mechanism 20. In other words, the subsequent decorticating members approached, but 70 stopped at a point short of, the subsequent gripping mechanism.

The third period will now be considered. During this period the decorticating members remain in the position just described 75 for a period of two-fifths of a second and during this interval of time the pusher or whip P is brought into operation so as to whip or push the cleaned fiber ends, from the butt end H, into gripping position between the jaws 55 and 56 of the subsequent gripping mechanism 20. The whip or pusher P and the cleaned ends are now gripped by the mechanism at 20. As soon as this operation is performed the main jaw 80 18 of the initial gripping mechanism is moved away from its gripping position and in fact is moved far enough away to permit the passage under the same of the decorticating members or tools which are carried on the arms 15 and 16 when they travel in the direction of the arrow marked B B. The opening movement of the movable jaw 85 18 of the initial gripping mechanism is accomplished through the medium of a spring 90 and is therefore comparatively quick.

The fourth period is the last to be considered and during this period the cycle of operations is completed. This period occupies one and two-fifths seconds and during it 100 the decorticating members are moved in the direction of the arrow B B. At the end of the second period the opposed decorticating members on arm 16 had been moved so as to be on opposite sides of the cleaned 105 portions of the fiber. At the beginning of the fourth period said decorticating members are started on their movement in the direction of the arrow B B. They are permitted to press upon portions of the fiber 110 which have been cleaned immediately upon the rollers 33 leaving the fixed stop or portion 94 of track J. During the rest of the movement in the direction of the arrow B B the decorticating members on arm 16 are enabled to perform their function of cleaning 115 the strip. During this period the strip is held by the subsequent gripping mechanism 20 and also by the friction of cleaned fiber pressing against the curved periphery of 120 the resisting member or drum 3. During the time a cleaning operation is being performed, by either the opposing members on the arms 15 or arms 16, it will be observed that the inner member or resistance members Y are located between the stock being treated and the resisting member or drum 3. When, however, the initial decorticating members on the arm 15 are traveling in 125 the direction of the arrow B B they are pass- 130

ing over and not in engagement with the stock which has been cleaned and which is then resting upon the resisting member 3 in the space Z. They are enabled to do this 5 because the movement in the direction of arrow A A is sufficient for the decorticating members on the arm 15 to pass beyond the clean butt end of the strip whereby when a reverse movement is subsequently imparted 10 to the decorticating members they can pass over the strip which is then gripped at 20. The movement in the direction of the arrow B B is more than a complete revolution and is sufficient to return the gear 14 and the 15 decorticating members carried or actuated thereby to the position shown in Figs. 2 and 3; in other words, to their initial position thus completing the cycle of operations.

From what has preceded it will be manifest 20 that the gear construction clearly shown in Figs. 9 to 15 can be employed to transfer the power from a continuously rotating shaft or motor to the main gear 14 and also to the main shaft 8 and that the mechanism 25 shown in said figures can be employed in place of the corresponding mechanism illustrated in Figs. 1 to 4; in fact the mechanism shown in Figs. 9 to 15 illustrates the preferred construction.

The machine previously described and clearly shown on the drawings is portable, is comparatively compact, affords a high speed of operation, requires only a comparatively small amount of power to operate, is 30 safe in its operation, and is highly efficient in its cleaning operation. The cleaning or decorticating members are readily adjustable. The opposing members of any set of decorticating members can be maintained in 35 the proper relation in respect to each other through the means of the contact block and the long powerful adjustable tension springs which tend to force the outer decorticating member or knife toward its inner decorticating member. The opposing decorticating 40 members are mounted so that they are open at one end whereby material to be treated can be inserted, by a lateral movement, into the space between the members. A projection or supporting member is provided on 45 one of the decorticating members for assisting in maintaining the free end of the opposing decorticating member in place relative to the decorticating member carrying 50 said projection or stop. Due to the curved periphery of the drum or resisting member some of the strain imparted to the clean fiber can be absorbed by the curved portion 55 of the drum against which it rests and will 60 consequently not have to be transmitted to the gripping mechanism holding the fiber in place at that particular time.

While the resisting member is shown as 65 being circular in form having a sheet metal periphery, still it will be manifest that the

resisting member can be made in other forms and that the resisting surface can be provided by means other than a sheet metal member as, for instance, a series of rods extending from one side of the resisting member to the other. 70

From what has preceded it will be observed that the decorticating members operate intermittently upon the stock which is held in place relative to the circular resisting 75 means, to wit, the drum 3. It will also be observed that the stock is held substantially stationary during the time that the entire portion thereof is being cleaned by the decorticating members which have an angular 80 movement relative to the drum 3 and which decorticating members also travel past the exterior of the gripping means.

It will also be manifest that the decorticating members move in different directions 85 to clean different portions of the stock; in other words, while the stock is being held stationary the decorticating members are moved in one direction to clean one portion of the stock and while the stock still remains substantially stationary and is held in said position the decorticating members move in an opposite direction to clean the remaining portion of the stock. 90

The improvements herein set forth are 95 not limited to the precise construction and arrangement shown and described for they may be embodied in various forms and modifications without departing from the spirit and scope of the invention. 100

What I claim is:

1. A machine of the class described comprising in combination a fiber resisting member, an initial set of gripping mechanism for securing the stock to be cleaned to the said resisting member, an initial set or sets of opposing decorticating members arranged to engage opposite sides of the stock when thus secured, means for moving said initial decorticating members when thus engaging the 105 stock toward and beyond one end of the stock for the purpose of cleaning said end, a subsequent gripping mechanism for securing the cleaned end of the stock to said resisting member, a subsequent set or sets of opposing 110 decorticating members arranged to engage opposite sides of the stock and to be moved toward the other end of the stock for the purpose of cleaning the rest of the stock, means for moving said subsequent decorticating members in a manner to perform their 115 function, the initial set of gripping mechanism being open during the latter cleaning operation whereby said subsequent decorticating members can pass from one side of said initial gripping mechanism along said resisting member to the other side of said initial gripping mechanism, the resisting member being shaped and said subsequent gripping mechanism being positioned rela- 120 125 130

- tive thereto so that during at least a portion of the time when said subsequent decorticating members are performing their cleaning operation some of the pull or strain on the 5 cleaned portion of the stock will be resisted by the resisting member against which the cleaned portion presses.
2. A machine of the class described comprising in combination a drum or fiber resisting member, an initial gripping mechanism for securing the stock to be cleaned to the drum or resisting member, an initial set or sets of opposing decorticating members, at least one of the decorticating members of 10 each set being a knife, one of the members of each initial set being arranged to engage the side of the stock which is farthest remote from the drum, the other member of each set being located between the exterior 15 of the drum and the stock when secured to the drum by said initial gripping mechanism, means tending to normally force the decorticating members of each initial set relatively toward each other, means for moving 20 said initial set or sets of decorticating members toward one end of the stock when in engagement with the stock, a subsequent gripping mechanism for securing to the drum the end portion of the stock when the 25 end portion has been cleaned, a subsequent set or sets of opposing decorticating members, one member of each subsequent set being located upon and engaging the side of the stock farthest from the resisting member or drum, the other or opposing member 30 of each set being located between the stock and the drum and engaging the side of the stock nearest to the drum, means tending to normally force the decorticating members of 35 said subsequent set relatively toward each other, and means for moving said subsequent set or sets of opposing decorticating members from a cleaned portion of the stock toward the other end of the stock so as to clean 40 the rest of the stock, the initial gripping mechanism being released so that said subsequent set or sets of decorticating members can be moved along the stock.
3. A machine of the class described comprising in combination a cylindrical drum or resisting member, an initial gripping mechanism for securing the stock to be cleaned to the drum, an initial set or sets of opposing decorticating members, a subsequent set or sets of opposing decorticating members, mechanism for supporting said initial and subsequent sets of decorticating members so that they can be moved along the periphery of the drum in one direction 50 at one time and so that they can be moved along the periphery of the drum in another direction at a subsequent time, the machine being constructed so that when said decorticating members are moved in one direction 55 the initial set or sets thereof are automatically brought into operation to clean one end of the stock, which stock is at that time secured to the drum by the initial gripping mechanism, a subsequent gripping mechanism that automatically grips the end of the 60 stock cleaned by the initial opposing decorticating members and so that when the sets of decorticating members are moved in a reverse direction the subsequent set of decorticating members will operate to clean the rest of the stock.
4. A machine of the class described comprising in combination a drum constituting a fiber resisting member, a frame carrying the same, a continuously rotating member 80 carried by said frame, a main bearing or shaft located at the central portion of said drum, a main gear having secured thereto members carrying an initial set or sets of decorticating members and a subsequent set 85 or sets of decorticating members, a train of gearing between the continuously rotating member and the main gear whereby the main gear and the sets of decorticating members thereupon will be moved in one 90 direction, as in a counter-clockwise direction, for a partial revolution and whereby the same main gear and sets of decorticating members thereupon will be automatically driven in a reverse direction, as in a clockwise 95 direction, for more than a revolution, an initial gripping mechanism, a subsequent gripping mechanism, controlling mechanism for said initial gripping mechanism, which controlling mechanism is operatively associated with said gearing whereby the initial gripping mechanism will grip stock to be operated upon, means associated with the initial set or sets of decorticating members whereby said members will be 100 caused to engage the stock when it is gripped by said initial gripping mechanism and will remain in operative engagement with said stock and thus clean an end of said stock while the main gear and the decorticating 105 members thereupon are being moved in one direction, as in the counter-clockwise direction, a second controlling mechanism associated with said train of gearing whereby said subsequent gripping mechanism will be 110 automatically brought into operation to seize the cleaned end of the stock, and means for automatically permitting the members of said subsequent set of decorticating members to operatively engage the stock when 115 the latter is secured in place by said subsequent gripping mechanism.
5. A machine of the class described comprising in combination a drum constituting a fiber resisting member, a frame carrying the same, a continuously rotating member 120 carried by said frame, a main bearing or shaft located at the central portion of said drum, a main gear having secured thereto members carrying an initial set or sets of 125

decorticating members and a subsequent set or sets of decorticating members, a train of gearing between the continuously rotating member and the main gear whereby the 5 main gear and the sets of decorticating members thereupon will be moved in one direction, as in a counter-clockwise direction, for a partial revolution and whereby the same main gear and sets of decorticating 10 members thereupon will be automatically driven in a reverse direction, as in a clockwise direction, for more than a revolution, an initial gripping mechanism, a subsequent gripping mechanism, controlling 15 mechanism for said initial gripping mechanism, which controlling mechanism is operatively associated with said gearing whereby the initial gripping mechanism will grip stock to be operated upon, means associated 20 with the initial set or sets of decorticating members whereby said members will be caused to engage the stock when it is gripped by said initial gripping mechanism and will remain in operative engagement 25 with said stock and thus clean an end of said stock while the main gear and the decorticating members thereupon are being moved in one direction, as in the counter-clockwise direction, a second controlling 30 mechanism associated with said train of gearing whereby said subsequent gripping mechanism will be automatically brought into operation to seize the cleaned end of the stock, and means for automatically permitting 35 the members of said subsequent set of decorticating members to operatively engage the stock when the latter is secured in place by said subsequent gripping mechanism, the machine being constructed so that 40 the decorticating members of the initial set will pass over the outer side of the stock which has been cleaned as the decorticating members are being moved in a clockwise direction, one member of each said subsequent 45 set being located on the outer side of the stock and the other member of each subsequent set being located between the inner side of the stock and the periphery of the drum during the entire period of travel 50 along the stock in both the counter-clockwise and clockwise directions, the members of said subsequent set or sets being held out of operative engagement with the stock during the travel of the members in the counter-clockwise direction 55 6. A machine of the class described comprising in combination a drum, a main bearing or shaft located at the central portion of the drum, a main member carried by said 60 shaft which main member supports thereupon a pair of arms one of which arms carries an initial set or sets of decorticating members and the other of which arms carries a subsequent set or sets of decorticating 65 members, and means for moving said

decorticating members at one time in one direction along the periphery of said drum and at another time in a reverse direction along said periphery.

7. A machine of the class described comprising in combination a drum, initial decorticating members, subsequent decorticating members, means for moving said decorticating members in one direction about a portion of the periphery of the drum at 70 one time and in a reverse direction at a subsequent time, an initial gripping mechanism for seizing one portion of a piece of stock and securing it to the drum while the initial decorticating members are being moved in 75 one direction to clean the stock, and a subsequent gripping mechanism for seizing another portion of the stock and securing it to the drum while said subsequent decorticating members are being moved in the 80 reverse direction to clean the rest of the stock.

8. A machine of the class described comprising in combination a drum, initial decorticating members, subsequent decorticating members, means for moving said decorticating members in one direction about a portion of the periphery of the drum at 85 one time and in a reverse direction at a subsequent time, and initial gripping mechanism 90 for seizing one portion of a piece of stock and securing it to the drum while the initial decorticating members are being moved in one direction to clean the stock, a subsequent gripping mechanism for seizing another portion of the stock and securing it to the drum while said subsequent decorticating members are being moved in the reverse direction to clean the rest of the stock, and a common means for moving the 95 decorticating members in the manner above described, for causing the gripping mechanisms to be brought into operation at the proper periods of time and for causing said gripping mechanisms to be automatically released at the proper periods of time.

9. A machine of the class described comprising in combination a resisting member having a circular periphery, decorticating members movable about the periphery, 115 initial and subsequent gripping mechanisms, and common means for actuating said decorticating members and said gripping mechanisms in a manner so that when the initial gripping mechanism is seizing one 120 portion of the stock to be cleaned the decorticating members will be moving in one direction to clean a portion of the stock and so that at a subsequent period the subsequent gripping mechanism will grip another portion of the stock and hold the same while the decorticating members are being moved in a reverse direction to clean the rest of the stock.

10. A machine of the class described com- 125

prising in combination a resisting member having a circular periphery, gripping mechanism for securing a piece of stock to said resisting member, and opposing decorticating members operating upon opposite sides of the stock and movable along the periphery so as to clean the stock thus gripped when the stock is between them.

11. In combination a resisting member, means for securing stock to the resisting member, which has a circular periphery, and a set or sets of coöperating opposing decorticating members movable in a path along said circular periphery.

12. A machine of the class described comprising in combination a resisting member, means for securing stock to be cleaned to said resisting member, decorticating members movable along said resisting member, means for feeding stock to be cleaned to said member, and means for ejecting the stock from said member in a direction toward that from which it was fed.

13. A machine of the class described comprising in combination a drum or resisting member, an initial gripping mechanism associated with said drum, decorticating members movable along the periphery of said drum, a work-table located at one side of said drum, feeding means for moving stock to be cleaned from the table into operative position relative to and over said drum, a receiving table or rack which is located at the same side of the drum as the feeding table, ejecting means for moving cleaned stock from the drum to said rack, and means common to said feeding mechanism, gripping mechanism, decorticating members and ejecting means whereby stock will be first fed to the machine from the table, gripped and cleaned respectively by the gripping mechanism and decorticating members and finally ejected from the periphery of the drum and transferred to the receiving table or rack.

14. A machine of the class described comprising in combination a resisting member or drum, an initial gripping mechanism, an initial set or sets of decorticating members, a subsequent set or sets of decorticating members, a subsequent gripping mechanism which subsequent gripping mechanism comprises a whip or pusher for pushing the cleaned portions of stock into the space between the jaws of the subsequent gripping mechanism, and common operating means for closing the initial gripping mechanism, for actuating the initial set or sets of decorticating members and moving the same in one direction away from the initial gripping mechanism, for causing the whip or pusher to come into operation, for closing the jaws of the subsequent gripping mechanism and for moving the subsequent

set or sets of decorticating members in a direction away from the subsequent gripping mechanism, the mechanism operating said initial and subsequent gripping mechanisms being constructed so that the initial gripping mechanism will be open after the subsequent gripping mechanism has been closed and so that the subsequent gripping mechanism will be open when the sets of decorticating members have performed their work.

15. A machine of the class described comprising in combination a circular resisting drum, a frame to which the drum is secured, a main driving shaft located centrally relative to the drum, a main driving gear revoluble relative to said shaft, decorticating members carried by said main gear which gear can be turned so as to move the decorticating members around the periphery of said resisting drum, an initial gripping mechanism associated with said drum, a subsequent gripping mechanism associated with said drum, a cam on said main shaft for controlling the opening and closing of the initial gripping mechanism, a cam on said shaft for controlling the opening and closing of the subsequent gripping mechanism, a continuously rotating shaft, mechanism between the continuously rotating shaft and the main shaft for continuously driving the main shaft, and mechanism between the continuously rotating driving shaft and the main gear whereby as the continuously driving shaft rotates an intermittent movement will be imparted to the main gear so as to move the decorticating members in one direction relative to said drum at one time and in a reverse direction at a subsequent time.

16. A machine of the class described comprising in combination a circular resisting drum, a frame to which the drum is secured, a main driving shaft located centrally relative to the drum, a main driving gear revoluble relative to said shaft, decorticating members carried by said main gear, which main gear can be turned so as to move the decorticating members along the periphery of said resisting drum, an initial gripping mechanism associated with said drum, a subsequent gripping mechanism associated with said drum, a cam on said main shaft for controlling the opening and closing of the initial gripping mechanism, a cam on said shaft for controlling the opening and closing of the subsequent gripping mechanism, a continuously rotating driving shaft, mechanism between the continuously rotating driving shaft and the main shaft for continuously driving the main shaft, and mechanism between the continuously rotating driving shaft and the main gear whereby as the driving shaft continuously rotates an intermittent movement will be imparted to the main gear so as to move the decorticating

- members in one direction relative to said drum at one time and in a reverse direction at a subsequent time, the cams on the main shaft being arranged so that the initial gripping mechanism is closed and the subsequent gripping mechanism is open when the decorticating members are being moved in one direction and so that the subsequent gripping mechanism is closed and the initial gripping mechanism is open when the decorticating members are being moved in a reverse direction.
17. A machine of the class described comprising in combination a circular drum or resisting member, gripping mechanism for securing a strip of stock to said resisting member, means for operating upon the stock when secured to said resisting member, feeding mechanism for moving stock to be cleaned from a position at one side of the drum to a position over the drum where said stock can be secured to the drum, ejecting mechanism for moving the stock from over the drum to a position at one side thereof after the stock has been cleaned, a continuously rotating main shaft having thereupon cams for controlling the operation of the gripping mechanism, for controlling the operation of the feeding mechanism and for controlling the operation of the ejecting mechanism.
18. A machine of the class described comprising in combination a resisting drum, a main gear for moving decorticating members along the periphery of said drum, a main shaft, gripping mechanism associated with said drum so as to secure the stock to the drum while it is being operated upon by said decorticating members as they move about the periphery of said drum, a feed table located at one side of the drum, feeding members movable from said table to a position where the stock moved thereby can be gripped by said gripping mechanism, a receiving rack located on the same side of the drum as the feed table, ejecting mechanism for moving stock which has been operated upon from the drum to said receiving rack, a cam on said shaft for controlling the operation of the feeding mechanism, a cam on said shaft for controlling the operation of said gripping mechanism, a cam on said shaft for controlling the operation of said ejecting mechanism, a continuously rotating driving shaft, gearing between said continuously rotating driving shaft and said main shaft so that the latter will be driven continuously, and gearing between the continuously rotating driving shaft and the main gear whereby a movement will be imparted to the main gear in one direction at one time and in a reverse direction at a subsequent time.
19. A machine of the class described comprising in combination a resisting drum, gripping mechanism associated with said drum, decorticating members movable along the periphery of said drum, a feed table located at the side of said drum, feeding means for moving a strip of stock from said table to a position where it can be secured in place relative to said drum by said gripping mechanism, and a common mechanism for controlling the operation of the gripping mechanism and feeding means.
20. A machine of the class described comprising in combination a drum or resisting member, gripping mechanism associated with said drum or resisting member, decorticating members movable along the periphery of said drum, a receiving rack located at one side of said drum, ejecting mechanism for moving stock which has been cleaned from a position on said drum to said receiving rack, and a common mechanism for controlling the operation of the gripping mechanism and the ejecting mechanism.
21. A machine of the class described comprising in combination a drum or resisting member, a feed table located at one side of the drum, a rack located at the same side of said drum, means for feeding stock from said feed table to a position over said drum, and means for moving said stock from said drum to said rack.
22. A machine of the class described comprising in combination a drum or resisting member, a feed table located at one side of the drum, a receiving rack located at the same side of said drum, means for feeding stock to be cleaned from said feed table to a position over said drum, means comprising decorticating members for cleaning the stock, means for ejecting said stock after it has been cleaned and moving it from said drum to said rack, and common means for controlling the actuation of the feeding means and the ejecting means.
23. A machine of the class described comprising in combination a drum or resisting member, gripping mechanism associated with said drum, decorticating members movable along the periphery of said drum, means for feeding stock to be cleaned from a position at one side of the drum to the gripping mechanism whereby said stock can be secured to said drum, mechanism for cleaning the stock, mechanism for moving the cleaned stock from said drum to the side from which it was originally fed, and common means for actuating the feeding means, the cleaning mechanism and the ejecting means.
24. A machine of the class described comprising in combination a drum or resisting member, a gripping mechanism associated with said drum, opposed decorticating members movable along the periphery of said

- drum, means for separating the opposed members of each set of decorticating members, means for feeding stock into the space between said opposed decorticating members when they are separated, mechanism for gripping the stock when in the space between the opposed decorticating members, and a common mechanism for operating said gripping mechanism and said feeding means.
25. A machine of the class described comprising in combination a drum or resisting member, a gripping mechanism associated with said drum, opposed decorticating members movable along the periphery of said drum, means for separating the opposed members of each set of decorticating members, means for feeding the stock from a position at one side of the drum to a position between said opposed decorticating members when they are separated, and mechanism for operating said gripping mechanism, said feeding means and said decorticating members.
26. A machine of the class described comprising in combination a drum or resisting member, a gripping mechanism associated with said drum, opposed decorticating members movable along the periphery of said drum, means for separating the opposed members of each set of decorticating members, ejecting means for moving the stock when cleaned from the drum to one side thereof, and common mechanism for operating said gripping mechanism and said ejecting means.
27. A machine of the class described comprising in combination a drum, decorticating members movable around the periphery of said drum, a main gear for actuating said decorticating members, a continuously rotating driving shaft, a train of gearing comprising a Geneva gear construction and an intermittent gear construction, and means whereby at one time the continuously driving shaft will drive the main gear through the Geneva gear construction in one direction and so that at another time the driving shaft will drive the main gear in a reverse direction through the intermittent gear construction.
28. A machine of the class described comprising in combination a drum, decorticating members movable along the periphery of said drum, a main gear for actuating said decorticating members, a continuously rotating driving shaft, a train of gearing comprising a Geneva gear construction and an intermittent gear construction, and means whereby at one time the continuously driving shaft will drive the main gear through the Geneva gear construction in one direction and so that at another time the driving shaft will drive the main gear in a reverse

direction through the intermittent gear construction, the gearing being constructed so that the main gear will be arrested at each end of its movement in the reverse direction for a period of time sufficient to allow other operations to be performed.

29. A machine of the class described comprising in combination a resisting member, an initial gripping mechanism associated with said resisting member, a subsequent gripping mechanism associated with said resisting member, an initial set of decorticating members and a subsequent set of decorticating members, both of which sets are movable along the periphery of said drum, the initial set of decorticating members being in operative position when moving in one direction and the subsequent set of decorticating members being in operative position when moving in a reverse direction, a main gear for actuating said sets of decorticating members, a continuously rotating driving shaft, gearing between the continuously rotating driving shaft and said main gear whereby said continuously rotating driving shaft will actuate and move said main gear in one direction at one time and in a reverse direction at another time, mechanism actuated by said continuously rotating driving shaft for controlling the opening and closing of said gripping mechanisms, the gearing between said continuously rotating driving shaft and the main gear being constructed so that at the end of each movement of the main gear and the decorticating members actuated thereby there will be a dwell for a sufficient period of time to permit the opening or closing of the gripping mechanisms, as the case may be.

30. A machine of the class described comprising in combination a drum or resisting member, gripping mechanism associated therewith, decorticating members movable along the periphery of said drum, a main gear for actuating said decorticating members in reverse directions, mechanism for feeding stock to a position where it can be gripped by the gripping mechanism and thus be secured to the resisting member while being cleaned by the moving decorticating members, a continuously rotating driving shaft, gearing between said continuously rotating driving shaft and said main gear for causing said main gear to move in one direction at one time and in a reverse direction at another time, mechanism for ejecting cleaned stock from the drum, and mechanism between said continuously rotating driving shaft and said feeding and ejecting mechanisms whereby said feeding mechanism will feed stock to be cleaned to the machine after the decorticating members have been moved in one direction and for ejecting cleaned stock from the machine

after the decorticating members have been moved in a reverse direction, said gearing between the continuously rotating driving shaft and the main gear being constructed so that the decorticating members are at rest during the time the feeding mechanism and ejecting mechanism are being operated, the machine being constructed so that the ejecting mechanism is operated to remove cleaned stock from the machine just preceding the time of inserting into the machine stock to be cleaned.

31. A machine of the class described comprising in combination a resisting member or drum, an initial gripping mechanism, a subsequent gripping mechanism, a main gear, a set or sets of initial decorticating members and a set or sets of subsequent decorticating members, which sets of decorticating members are actuated by said main gear, a continuously rotating driving shaft, gearing between said continuously rotating driving shaft and said main gear, whereby the main gear can be given an initial movement for a partial rotation in one direction, as in a clockwise direction, and a subsequent movement in a reverse direction, as in a counter-clockwise direction, for more than a revolution and back to its original position, mechanism actuated by said continuously rotating driving shaft for controlling the opening and closing of the initial and subsequent gripping mechanisms, the gearing being constructed and timed so that the initial gripping mechanism will be closed and will remain closed while the main gear is moving the initial set of decorticating members in the counter-clockwise direction to clean a portion of the stock so that at the end of this initial cleaning operation a cleaned portion of the stock will be automatically gripped by the subsequent gripping mechanism and will be secured to said drum while the subsequent decorticating members are being moved in the clockwise direction to the uncleared portion of the stock, the initial gripping mechanism being open during the subsequent cleaning operation whereby said subsequent decorticating members can perform their work upon the portion of the stock which was previously gripped by the initial gripping mechanism.

32. A machine of the class described comprising in combination a resisting member or drum, means for securing stock to be cleaned to said drum, a set or sets of opposing decorticating members movable along the periphery of said drum, one member of each set being located between the periphery of the drum and the stock being cleaned, the other member of each set being located on the side of the stock which is farthest remote from the drum, the forward face of

the decorticating members being inclined 65 rearwardly from the drum so that in its forward movement along the stock being cleaned any material removed from the stock can be freed from the machine.

33. A machine of the class described comprising in combination a continuously rotating shaft, a set of intermeshing twin gears actuated thereby and rotating in opposite directions, a cam construction actuated by said twin gear construction, a main gear, 70 a floating gear construction for driving said main gear, means actuated by said cam construction for positioning and holding said floating gear construction so that in one position the floating gear construction will be 80 driven from a gear of a train of gears which comprises a Geneva gear construction in which Geneva gear construction there is a roller or pin that actuates a notched gear thereof, and which roller or pin is actuated 85 by one of said twin gears, and so that in another position the floating gear construction will be actuated from a gear of a train of intermittent gears, one of which intermittent gears is actuated by the other of 90 said twin gears.

34. A machine of the class described, comprising in combination a continuously rotating shaft, a set of intermeshing twin gears actuated thereby and rotating in opposite directions, a cam construction actuated by said twin gear construction, a main gear, a floating gear construction which drives said main gear, means actuated by said cam construction for positioning said 95 floating gear construction so that when the floating gear construction is in one position it in turn will be driven from a gear of a train of gears which comprises a Geneva gear construction in which the roller or 100 pin that actuates the notched gear is actuated by one of said twin gears and so that when the floating gear construction is in another position the floating gear construction will be actuated from a gear of a train 105 of intermittent gears one of which is actuated by the other of said twin gears, the train of Geneva gearing and train of intermittent gearing being constructed and timed relative to the cam construction so that the 110 movement of the floating gear construction, either to or from a position where it will be driven, will take place when the members that drive it are idle.

35. A machine of the class described comprising in combination a drum, an arm extending from the central portion of the drum toward the periphery thereof, said arm carrying thereupon one of the members of a set of opposing decorticating members, 115 a member slidably mounted on said arm and carrying the other member of the set of opposing decorticating members, and a

tension spring one end of which is secured to said arm and the other end of which is secured to the member slidably mounted upon said arm.

5 36. A machine of the class described comprising in combination a drum, an arm located at the side of said drum, said arm carrying a block which extends from said arm laterally across the periphery of the

10 drum, a decorticating member mounted on said block, a member movably mounted upon said arm and having secured thereto a decorticating member which is opposed to a

15 decorticating member on said block, and a spring secured to said arm and to the member movably mounted thereupon which spring normally tends to force the decorticating members toward each other.

37. A machine of the class described comprising in combination a drum, an arm located at the side of said drum, said arm carrying a block which extends from said arm laterally relative to the periphery of

20 the drum, a decorticating member on said block, a carrying member movably mounted upon said arm and having secured thereto a decorticating member which is opposed to a decorticating member upon the resisting block, and a spring between said arm and

25 30 the carrying member, which spring normally tends to force the decorticating members toward each other, the block carrying a resisting pin at the end which is farthest from the arm, which pin is or can be engaged by the decorticating member on the carrying member whereby a thrust against the knife can be resisted by the said pin.

38. In the cleaning of fibrous material the method which comprises gripping the stock

40 to be cleaned in a manner to secure it to a resisting member, moving decorticating members away from the gripped portion of the stock and toward and past one end of the stock so as to clean the fiber in said end

45 of the stock, gripping the cleaned end so as to secure it to the resisting member, releasing the first grip on the stock and moving the decorticating members away from the cleaned fiber toward the uncleared end so as 50 to clean the entire length of fiber in the strip.

39. The cleaning of fiber which is in a strip or stock of fiber bearing material by the method which comprises employing a fiber resisting member having a curved periphery, securing the strip or stock to the periphery of the resisting member, moving a set of decorticating members along the stock away from the gripped portion to- 55 ward and past one end of the stock so as to clean the fiber in one end, securing the cleaned fiber to the resisting member in a manner so that the cleaned fiber will rest

against a curved portion of said resisting member, releasing the strip or stock at the 65 gripping the said decorticating portion of decorticating members from the cleaned portion of the stock toward the uncleared end of the stock so as to effect the cleaning of the other portion of the fiber. 70

40. In the isolating of fiber from stocks of fibrous bearing material, the method which comprises securing the stock to one portion of a resisting member having a curved periphery operating upon said stock 75 by means of decorticating members which engage opposite sides of the stock and which move away from the place where gripped toward one end of the stock so as to clean said end, securing said cleaned end in a 80 manner so that the cleaned fiber will rest against a curved portion of the periphery of the resisting member, releasing that portion of the fiber which was first secured to the resisting member and cleaning other 85 portions of the fiber by means of decorticating members that engage opposite sides of the strip or stock and that move from the cleaned portion toward the uncleared end of the stock while the stock is held in place 90 relative to the resisting member with cleaned portions of the fiber resting against a curved portion of the periphery of the resisting member.

41. The method of decorticating fibrous 95 stock detached from the plant, which method comprises holding the stock substantially stationary and while so holding it decorticating the entire stock.

42. The method of decorticating fibrous 100 stock detached from the plant, which method comprises gripping one portion of the stock, decorticating another portion of the stock, gripping the said decorticitated portion of the stock and decorticating the said first 105 portion, thereby decorticating the entire stock, the stock remaining substantially stationary from the commencement of the first decorticating operation to the end of the second decorticating operation. 110

43. A machine of the class described comprising in combination a resisting member having a circular periphery, gripping mechanism for securing a piece of stock to said resisting member, and opposing decorticating 115 members operating upon opposite sides of the stock and movable along the periphery so as to clean the entire stock.

44. In a decorticating machine, two sets of decorticating means, circular resisting means common to said sets of decorticating means, and means for intermittently operating one of the said sets of decorticating means with respect to the other of said sets of decorticating means, the construction being such that when one of said sets of de- 125

corticating means is in operation it moves in one direction relative to said resisting means and when the other of said sets of decorticating means is in operation it moves 5 in the opposite direction relative to said resisting means.

45. A decorticating machine comprising a circular resisting member, means for securing a piece of stock so that it will 10 extend along the periphery of the said member and so that the entire stock can be decorticated, and means for decorticating the entire stock when, along said member and while secured by said first-mentioned means. 15 46. In a decorticating machine, a stationary circular resisting member, decorticating means, and means for intermittently moving the decorticating means in opposite directions along the resisting member so as to 20 decorticate the stock for its entire length.

47. In a decorticating machine, a resisting member, means for securing stock thereto, and means constructed and arranged so that due to movement in opposite directions 25 the entire length of the stock can be decorticated.

48. In a Manila hemp decorticating machine, means for decorticating a piece of stock and means for holding the stock in a 30 substantially stationary position while decorticating the entire piece.

49. In a decorticating mechanism for fibrous plants, means for decorticating the entire piece of stock, a plurality of gripping mechanisms, one member of each gripping mechanism being stationary, and means to operate the gripping mechanisms relative to the decorticating means.

50. In a machine of the class described, 40 a resisting member, means for gripping the stock acted upon, and a series of angularly movable decorticating members, said decorticating members being movable in a path exterior to the gripping means, said gripping means having a movable jaw located 45 between the path of the decorticating members and the main body of the resisting member.

51. In combination, a resisting member, 50 means for securing stock to the resisting member, and reversing decorticating members movable along the resisting member to decorticate the entire piece of stock.

52. In combination, a stationary resisting member, means for securing stock to the stationary resisting member, and decorticating members movable in one direction at one time and in a reverse direction at another time along the stationary resisting member 60 to decorticate the entire piece of stock.

53. A machine of the class described comprising in combination a circular resisting member, gripping mechanism for securing a

piece of stock to said resisting member, and decorticating members for decorticating the 65 entire stock thus gripped while it remains in substantially the same position relative to the resisting member.

54. In combination, means for gripping a piece of stock and for holding the same substantially stationary, and means for cleaning the entire stock so gripped. 70

55. In a machine of the class described, means for holding stock substantially stationary, decorticating means movable in one 75 direction at one time and in reverse direction at another time, and means for moving the decorticating means in said directions to decorticate different portions of the stock, the decorticating means being movable in 80 such a manner that the entire length of stock is subjected to the operation of said means.

56. In a machine of the class described, mechanism movable in one direction at one 85 time and in a reverse direction at another time, and decorticating means carried by said mechanism, said means being so constructed that it decorticates a portion of the stock when said means is being moved in 90 one direction by said mechanism and so that the entire remaining undecorticated portion of the stock is decorticated when the decorticating means is being moved in a reverse direction by said mechanism. 95

57. In a machine of the class described, means for gripping a piece of stock, means for cleaning a portion of the stock, means for gripping the portion so cleaned, and means for cleaning the portion originally 100 gripped, said stock being at all times substantially stationary.

58. In a machine of the class described, means for gripping a piece of stock, means for cleaning a portion of the stock, means for gripping the portion so cleaned, and means for cleaning the portion originally gripped, the construction being such that said stock remains substantially stationary 105 during the series of operations of said means. 110

59. In a machine of the class described, the combination of means for gripping a piece of stock, and a set of opposing decorticating members arranged to simultaneously engage opposite sides of the stock thus 115 gripped, which decorticating members are movable in a curvilinear path.

60. A machine of the class described comprising means for gripping a piece of stock, means for decorticating one end of the stock, 120 means for gripping the decorticated end, and means for decorticating the remainder of the stock, said gripping means operating to hold the stock in a substantially stationary position throughout the decorticating 125 operation.

61. In a machine of the class described, means for feeding stock, means for holding the stock substantially stationary, and means for decorticating the entire stock while thus held.

62. In a machine of the class described, means for holding the stock substantially stationary, means for decorticating the entire stock while thus held, and means for 10 ejecting the cleaned stock.

63. In a machine of the class described,

means for feeding stock, means for holding it substantially stationary, means for decorticating the entire stock while thus held, and means for ejecting the decorticated 15 product.

This specification signed and witnessed this 25th day of July, A. D. 1916.
